CHESTER W. CRUMRINE, OF ROCHESTER, NEW YORK, ASSIGNOR TO ELECTROMATIC TYPEWRITERS, INC., OF ROCHESTER, NEW YORK, A CORPORATION OF NEW YORK

TYPEWRITING MACHINE

Application filed March 5, 1931. Serial No. 520,941.

This invention relates to improvements in typewriting machines, and particularly to power driven typewriting machines in which the type selection is or may be mechanically controlled by means of a perforated master sheet.

The principal object of the invention is to provide simple and inexpensive means for locking the controlling devices against actuation when the master sheet is not properly arranged in the machine.

Another object of the invention is the provision of simple and efficient means for preventing the insertion of the roller for the master sheet when the actuating devices for the roller are operating.

In machines of this kind, the actuation of the master sheet roller is usually controlled by a key or lever, and it is the object of this invention to provide simple means for automatically locking the key or lever against operation to actuate the master sheet roller when the roller or its sheet are not in proper position in the machine.

More specifically, it is the object of this invention to provide resilient means for locking the controlling lever against operation to connect a master sheet roller with its driving means when either the roller, the master sheet, or the sheet guard are not in proper position in the machine, said means being also operative to prevent the insertion of the master sheet roller when the control lever is in position to connect the master sheet roller with its driving means.

To these and other ends, the invention consists in the construction and arrangement of parts that will appear from the following description when read in conjunction with the accompanying drawings, the novel features being pointed out in the claims at the end of the specification.

In the drawings:

Fig. 1 is a transverse section through the sheet controlled devices of an automatically controlled typewriting machine illustrating one possible embodiment of the invention, the sheet controlled devices being disconnected from their driving means.

Fig. 2 is a similar view showing the posi-

tion of the parts when the master control sheet is removed;

Fig. 3 is a view also similar to Fig. 1 but showing the position of the parts when the sheet guard is removed;

Fig. 4 is a similar view showing the position of the parts when the sheet controlled devices are connected with their driving means and the master sheet roller is removed;

Fig. 5 is a detail perspective view of a lever for connecting and disconnecting the master sheet roller with its driving means;

Fig. 6 is a detail view in side elevation of a feeler which controls the interlocking devices;

Fig. 7 is a similar view of a locking dog, and

Fig. 8 is a similar view of an interlocking dog.

Referring particularly to the drawings, in which like reference numerals refer to the same part in all the views, 1 represents a key lever of a typewriting machine having a key 2 and operatively connected with devices for actuating type bars, of usual or well known construction. It will be understood that a plurality of the key levers 1 are employed, one for each of the type bars to be actuated. Each of the key levers 1 is slidably connected with the upper end of a link 3, the lower end of which is pivoted to the rear end of an actuating lever 4 pivoted at 5 to the frame. The construction is such that when the key lever is depressed, it slides on the link without imparting any movement thereto. When, however, a pull is exerted on the link, it operates to depress the key lever. Revolubly mounted on the forward arm of the lever 4 is a star wheel 6 arranged in juxtaposition to a power actuated master sheet roller 7.

The roller 7 is provided with depressions 8 forming projections 9 between them, which are adapted to engage the arms of the star wheel to turn it on its lever, whereby the front end of the lever is cammed away from the roller against the tension of a spring 4' to depress its rear end to actuate the key lever. Means are provided for controlling the interengagement of the star wheels with the roller, comprising a master sheet 10 provided

with suitable perforations adapted to register with the arms of the star wheels and arranged on the roller between it and the star wheels. The construction is such that the 5 star wheels ride on the master sheet until one of its perforations moves into registration with the arm of a star wheel and permits the arm to move through the sheet into engagement with one of the depressions in 10 the roller and turns the star wheel to actuate the type bar.

In order that the machine may be operated either manually or automatically by means of the master sheet, as when the name 15 and address is manually written in the heading of a circular letter, the body of which is written by the master sheet controlled devices, it is desirable that means under the control of the operator be provided for operatingly connecting and disconnecting the master roller with its driving means. To this end, a stub shaft 12 is operatively connected to one end of the master roller and has a worm wheel secured thereto which is operatively engaged by a worm on a shaft 13 axially aligned with a driven shaft 14 having a clutch member 15 on its forward end. A cooperating clutch member 16 is keyed to the rear end of the shaft 13 to move into and out 20 of engagement with the clutch member 15. A hand actuated lever 17 is pivoted at 18 on a bracket fixed to the frame and is provided with a stud 19 which projects laterally therefrom and engages a groove 20 provided therefor in the clutch member 16. Movement of the lever 17 from the position shown in Fig. 1 to that shown in Fig. 4 25 serves to engage the clutch and operatively connect the worm with the driven shaft 14. 40 Forward movement of the lever serves to disengage the clutch and again disconnect the master roller from its driving means.

At its lower end, the lever 17 is bent forwardly and downwardly to form an arm 22, then laterally to form a connecting or locking arm 23 and again upwardly and rearwardly to form an arm 24 substantially parallel with the arm 22 and also engaging the pivot 18, and serves to prevent any lateral 50 thrust of the lever 17. From an inspection of the drawings, it will be noted that the lever 17 is pivoted directly in rear of the power driven roller 7. Pivoted on a bracket 25 forwardly of the lever 17, and to the rear 55 of the power driven roller is a feeler in the form of a dog 26 shown in detail in Fig. 6. Arranged beneath the roller 7 is a removable guard 27 having front and rear walls over which the master sheet is guided to and from 60 the power driven roller. The rear wall 28 of the guard is slotted at 29 to provide a clearance for the forward or sensitive arm 30 of the feeler. A spring 31 is connected to the feeler 26 at one end, and at its other end is 5 anchored to the bracket 25 and serves to

swing the feeler resiliently into engagement with the master sheet as shown in Fig. 1, or through the slot 29 into engagement with the roller 7 when the sheet is absent, as shown in Fig. 2.

The feeler 26 has a downwardly and rearwardly projecting arm 32 which engages a stud 33 projecting laterally from a locking dog 34 pivotally mounted on the bracket 25 concentric with the feeler 26. A spring 35 connected at one end with the stud 33 serves to resiliently swing the dog 34 with its lug 33 resiliently engaging the arm 32 on the feeler. The locking dog 34 is shown in detail in Fig. 7, from an inspection of which figure it will be seen to have a cam locking surface 36 terminating in an abrupt shoulder 37 at its forward end. When the clutch is disengaged and there is no master sheet on the roller 7 the feeler occupies the position shown in Fig. 2, as previously explained, under the action of its spring 31. This movement swings its arm 32 downwardly and forwardly from the position shown in Fig. 1 to that shown in Fig. 2, and permits the locking dog 34 also to swing downwardly and forwardly under the action of its spring 35 and move its cam or locking surface 36 over and into engagement with the arm 23 on the lever 17 and locks said lever against actuation in a direction to close the clutch. It will be noted from the above that unless the master sheet is in position on the master roller, the lever 17 is locked so that it cannot be operated to engage the clutch, since engagement of the clutch at this time might cause serious injury to the parts since all the type bars would be actuated simultaneously.

Before a new master sheet can be inserted in the machine, it is necessary to remove the guard 27, and before the guard is replaced, the feeler again moves into engagement with the roller 7 and carries the newly inserted sheet with it to the position shown in Fig. 3, in which position the parts again occupy substantially the same position as in Fig. 2, and the locking dog 34 again engages the part 23 of the lever 17 and prevents actuation thereof to close the clutch.

As previously stated, the power driven roller 7 is disengaged from the machine when it is desired to place a new master sheet thereon. If the clutch be engaged at this time, the roller would be driven as soon as connected with the machine and again the type bars would be simultaneously actuated with disastrous results if the roller were inserted without the sheet. It is therefore desirable to provide means for preventing the insertion of the master sheet roller when the clutch is engaged. To this end, a second locking dog 40, shown in detail in Fig. 8, is pivoted on the feeler at 41 and connected to the other end of the spring 35. The spring 35 serves to normally swing the dog 40 in a

direction to resiliently move a forwardly projecting arm 42 thereon into engagement with the feeler. If the lever 17 be moved from the Fig. 1 position to close the clutch, its arm 23 will be moved forwardly relatively to the dog 34, and if the guard and the roller with its master sheet be now removed, the feeler and the parts controlled thereby will move to the position shown in Fig. 4. As the feeler moves forward from the Fig. 1 position, its movement is limited by the engagement of its arm 32 with the rear surface of the arm 23 of the lever 17, which arm is also engaged by the shoulder 37 on the dog 34 which also limits the forward movement of the dog. The dog 40 is also carried forward with it until its rear or tail end swings against the front face of the arm 23 under the action of the spring 35. This position of the parts is shown in Fig. 4, and it will be noted that when the parts are in this position, the feeler occupies the position normally occupied by the master roller, and that the engagement of the dog 40 on the feeler with the lever 17 locks the feeler in this position so that the roller cannot now be inserted in the machine. However, if the lever 17 be moved to disengage the clutch, its arm 23 is moved downwardly and rearwardly out of the path of the dog 40, which releases the feeler and permits it to be manually moved out of the path of the master sheet roller against the tension of its spring 31 so that the roller can be inserted in the machine.

Although only one embodiment of the invention is shown and described herein, it will be understood that this application is intended to cover such changes or modifications as come within the spirit of the invention or scope of the following claims.

I claim:

1. In a typewriting machine, the combination of a frame, key levers and power actuated means for selectively operating said key levers, said means comprising a source of power, a revolute master sheet roller, manually actuated means for operatively connecting said master sheet roller with said source of power, means actuated by said master sheet roller for operating the key levers, a master sheet for controlling the operation of the key levers, and means controlled by the presence or absence of the master sheet for controlling the operation of said manually actuated means.

2. In a typewriting machine, the combination of a frame, key levers and power actuated means for selectively operating said key levers, said means comprising a source of power, a revolute master sheet roller, manually actuated means for operatively connecting said master sheet roller with said source of power, means actuated by said master sheet roller for operating the key levers, a

master sheet for controlling the operation of the key levers, locking means for controlling the operation of said manually actuated means, and a feeler arranged to resiliently engage the master sheet for controlling said locking means. ⁷⁰

3. In a typewriting machine, the combination of a frame, key levers and power actuated means for selectively operating said key levers, said means comprising a source of power, a revolute master sheet roller, a manually actuated lever for operatively connecting said master sheet roller with said source of power, means actuated by said master sheet roller for operating the key levers, a master sheet for controlling the operation of the key levers, a dog movable into engagement with said manually actuated lever for locking said lever against actuation to connect the master sheet roller with the source of power, and a feeler resiliently engaging the master sheet for controlling the movement of said dog. ⁷⁵ ⁸⁰

4. In a typewriting machine, the combination of a frame, key levers and power actuated means for selectively operating said key levers, said means comprising a source of power, a revolute master sheet roller, a manually actuated lever for operatively connecting said master sheet roller with said source of power, means actuated by said master sheet roller for operating the key levers, a master sheet for controlling the operation of the key levers, a dog movable into engagement with said manually actuated lever for locking said lever against actuation to connect the master sheet roller with said source of power, a feeler resiliently engaging the master sheet, and resilient means operatively connecting said feeler with said dog. ⁹⁰ ⁹⁵ ¹⁰⁰ ¹⁰⁵

5. In a typewriting machine, the combination of a frame, key levers and power actuated means for selectively operating said key levers, said means comprising a source of power, a revolute master sheet roller, a manually actuated lever for operatively connecting said master sheet roller with said source of power, means actuated by said master sheet roller for operating the key levers, a master sheet for controlling the operation of the key levers, a locking device for locking said manually actuated lever against actuation to connect the master sheet roller with said source of power, a feeler resiliently engaging the master sheet for controlling the movement of said locking device, and a guard for retaining the master sheet in the path of the feeler. ¹¹⁰ ¹¹⁵ ¹²⁰

6. In a typewriting machine, the combination of a frame, key levers and power actuated means for operating said key levers, said means comprising a source of power, a revolute master sheet roller detachably mounted in the frame, manually actuated ¹²⁵ ¹³⁰

means for operatively connecting and disconnecting said master sheet roller with said source of power, means actuated by said master sheet roller for operating said key levers, a feeler automatically movable into the path of the master sheet roller when the latter is detached, and means controlled by said manually actuated means for locking said feeler in the path of the master sheet roller.

7. In a typewriting machine, the combination of a frame, key levers and power actuated means for operating said key levers, said means comprising a source of power, a revolute master sheet roller detachably mounted in the frame, manually actuated means for operatively connecting and disconnecting said master sheet roller with said source of power, means actuated by said master sheet roller for operating said key levers, a feeler automatically movable into the path of the master sheet roller when the latter is detached, and a dog on said feeler adapted to engage said manually actuated means when the latter is in position to connect the master sheet roller with the source of power to lock the feeler in the path of the master roller.

8. In a typewriting machine, the combination of a frame, key levers and power actuated means for operating said key levers, said means comprising a source of power, a revolute master sheet roller detachably mounted in the frame, manually actuated means for operatively connecting and disconnecting said master sheet roller with said source of power, means actuated by said master sheet roller for operating said key levers, a feeler, a resilient means for moving the feeler into the path of the master sheet roller when the latter is detached, a locking dog movably mounted on the feeler and adapted to engage said manually actuated means to lock the feeler in the path of the master sheet roller, and resilient means for moving the dog to locking position, the arrangement being such that the dog moves to locking position when the master sheet roller is detached and the manually actuated means is in position to connect the master sheet roller with the source of power, but is inoperative to lock the feeler when the manually actuated means is in position to disconnect the master sheet roller from the source of power.

9. In witness whereof I have hereunto signed my name,

CHESTER W. CRUMRINE.
